CLAIM

The ornamental design for a bed cover, as shown and described.

DESCRIPTION

FIG. 1 is a front, left, and bottom perspective view of a bed cover, showing our design.

FIG. 2 is a rear, right, and top perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled 9 in FIG. 1 comprising of hook and loop; and,

(Continued)

FIG. 10 is another front, left, and bottom perspective view of FIG. 1 comprising of hook and loop in a condition of use. The broken lines shown in the drawings are included for the purpose of illustrating portions of the bed cover that form no part of the claimed design. Additional dash-dot broken lines in FIGS. 1 and 9 depict the boundaries of the enlarged view and form no part of the claimed design.

1 Claim, 10 Drawing Sheets
